UNITED STATES PATENT OFFICE

2,429,110

HEAT CRADLE

Otto Staloch, Vancouver, Wash.

Application November 29, 1945, Serial No. 631,577

1 Claim. (Cl. 219—45)

1

This invention relates to a heat cradle especially adapted to give heat treatments to various parts of the human body.

An object of this invention is to provide a device which is adapted to give heat treatment for diseases of the hands and arms, feet and legs of a human being, which is simple, in operation and structure and economical to manufacture.

With the above and other objects in view the invention consists of the novel features of construction, arrangement and combination of parts more fully hereinafter described, claimed and illustrated in the accompanying drawing in which:

Figure 1 is a perspective view of an embodiment of the invention and

Figure 2 is a detailed view of the strap for holding the patient's limb in the device.

Referring more in detail to the drawing the numeral 10 designates the cradle which comprises longitudinally extending base members 12 which are positioned parallel to and in opposed relationship to each other, at the ends of the members 12 semi-elliptical members 14 and secured thereto by rivets 16 or similar fastening means.

Secured to the top center of the members 14 by means of rivets 18 is a longitudinally extending member 20. At the center of the member 20 a semi-circular member 22 is secured thereto by rivets 24 and the ends of the member 22 are secured to the longitudinally extending members 26 which are parallel to the members 14 at each side thereof and in spaced relation thereto by rivets. The ends of the members 26 are secured to the members 14 by rivets 30.

The base members 12 are provided with a plurality of elongated slots 32 which are positioned adjacent each end thereof and at the center thereof.

The slots 32 are adapted to receive transversely extending members 34 which are slidably mounted in the slots and retained therein, in adjusted positions by means of bolts 36 having wing nuts 38 thereon.

Secured to the intermediate member 34 by means of a pin 40 is a strap 42 having an adjustable buckle 44, thereon and the end of the strap 42 is bound at 46 to prevent fraying thereof.

Except for the strap the cradle is made of rust proof strap iron members and instead of securing the members by rivets they may be assembled by welding.

In Figure 1 there is shown the manner in which the device is used.

2

A pillow is positioned beneath the cradle on which the patient's arm or leg rests and the strap is fastened about the wrist or ankle and the member to which the strap is fastened is susceptible of adjustment in several ways. Heat can be supplied to the cradle in many a well known way, but usually a light bulb is used and it may be attached to any of the members 14, 20 or 22 as desired.

Thus there has been provided a device which is very beneficial in giving heat treatment and it is believed the operation and construction thereof will be apparent to those skilled in the art.

It is to be understood that the embodiment described as illustrated is merely an example of one embodiment of the invention and that changes may be made in the details of construction, arrangement and combination of parts without departing from the spirit of the invention or the scope of the appended claim.

Having thus described the invention what is claimed as new and desired to be secured by Letters Patent is:

A device of the character described, comprising a cradle for heat treatment, comprising parallel elongated base members, semi-elliptical members secured to the ends of said base members, parallel longitudinally extending members secured to said elliptical members in spaced relation to said base members, a longitudinally extending member secured to the top of said semi-elliptical members at the top center point thereof, a semi-circular member secured to said last mentioned longitudinally extending member at the center point thereof, elongated longitudinally extending slots in said base members adjacent the opposite ends and at the center point thereof, transversely extending members adjustably secured to said base members by means of the slots at the ends thereof and at the center point thereof and means on one of said transversely extending members for holding the limbs of a patient.

OTTO STALOCH.
